UNITED STATES PATENT OFFICE.

GODFREY LOWELL CABOT, OF BOSTON, MASSACHUSETTS.

LAUNCHING MECHANISM FOR AIRCRAFT.

1,272,211.

Specification of Letters Patent.

Patented July 9, 1918.

Application filed August 13, 1917. Serial No. 186,012.

To all whom it may concern:

Be it known that I, GODFREY L. CABOT, a citizen of the United States, residing at Boston, in the county of Suffolk and State 5 of Massachusetts, have invented certain new and useful Improvements in Launching Mechanism for Aircraft; and I do declare the following to be a full, clear, and exact description of the invention, such as will 10 enable others skilled in the art to which it appertains to make and use the same.

My invention relates to improvements in apparatus for launching aircraft such as aeroplanes and hydroaeroplanes, the principal object being to provide magnetic means for holding the aircraft upon the launching apparatus until the required speed has been attained, and for then releasing it.

A further object is to provide electric 20 means for operating the launching apparatus and means for simultaneously cutting off the current from said operating means and the electro-magnetic holding means when the ship is traveling at a safe speed 25 for flight.

Yet another object is to provide a track 30 for the catapult carriage upon which said carriage and aircraft move forward under the power of the latter or of both for a predetermined distance, the electric propelling means of the carriage and the electric magnet being then automatically thrown 35 into action so that the craft is gradually driven faster until a safe flying speed is attained.

A still further object is to provide an apparatus well adapted for launching torpedo carrying aeroplanes and hydroaeroplanes, and to this end, an additional object is to 40 cause the torpedo or torpedoes to act as the sole connecting means between the airplane and the car on which it is launched into the air.

Another object is to provide a launching 45 apparatus which is adaptable equally well for use on the deck of a vessel or on land.

Still another object is to provide a novel and efficient method for launching numerous types of airplanes, even though the features 50 of construction hereinafter described, be radically changed.

With the foregoing general objects in view, the invention resides in the novel construction and combination and in the 55 launching method hereinafter fully described and claimed, the descriptive matter

being supplemented by the accompanying drawings which form a part of this specification and in which:—

Figure 1 is a side elevation of the improved catapult showing a torpedo carrying aeroplane mounted thereon in position for launching;

Fig. 2 is a front elevation of Fig. 1;

Fig. 3 is a top plan view of the launching track;

Fig. 4 is a plan view of the mechanism for releasing the torpedo from the airship; and

Fig. 5 is a longitudinal section on the plane of the line 5—5 of Fig. 4.

Heretofore the use of airplanes for carrying torpedoes has been restricted to comparatively small torpedoes, and for the reason that seaplanes have alone been used for this purpose, and the weight of the pontoons, without which the seaplane could not ascend from the water, has added a very considerable weight, and also greatly increased the head-on resistance of the air to the passage of the flying machine through it.

Under the proposed plan, all four (4) pontoons with their attachments are dispensed with, and their weight is added to the weight of the torpedo, which can be carried by the airplane.

Furthermore, inasmuch as the torpedo causes very little head-on resistance, a saving in the power required to propel the airplane at flying speed is also made, and the power thus saved becomes available for the suspension of additional weight.

There also are minor savings in that the wings can be built lighter in certain portions where in the usual type they have to be strengthened to support the attachment of the various pontoons. The net result is that nearly ten times as much weight can be carried on an airplane by the method of construction herewith described, and in excess of the water, gasolene, etc., needful for practical military operations, as by methods heretofore in use.

Briefly speaking, the improved mechanism comprises a car C, electro-magnetic means E for holding an airship thereon, electric driving means D for the car, and means M for simultaneously cutting off the current of the electro-magnetic means E and the driving means D, when the car and airplane carried thereby have attained a required speed.

The car C includes a suitable carriage 1 having flanged wheels 2 traveling on a pair of rails 3 which are laid in the form of a common type of track. The electric driving means D is in the form of an electric motor operatively connected to the wheels of the carriage 1, by suitable gearing 4, the current being supplied to said motor from the rails 3 and a third rail 5 which is illustrated in Figs. 2 and 3. A current conducting wire 6 leads from a suitable brush or the like, engaging one of the axles, to one binding post of the motor D, whereas a second wire 7 leads from the other binding post to a shoe 8 which travels upon the third rail 5. A similar arrangement is employed for supplying the current to the electro-magnetic means E, said arrangement consisting of a wire 9 which leads to said means from one of the axles, a second wire 10 extending from said means, and a shoe 11 electrically connected with said second wire and traveling on the third rail 5. It is to be understood that the means shown for supplying the current to the electro-magnetic means E and the driving means D are for illustrative purposes only, and that any preferred arrangement could well be employed. Furthermore, although a third rail will in most cases be employed, any other suitable arrangement such as a trolley wire might well be employed in some instances.

The means M for simultaneously cutting off the current of the electro-magnetic means E and driving means D, is preferably in the form of a common type of rheostat. By this means, the speed of the driving mechanism may be gradually increased as the carriage travels forward and then, at the proper time, the circuit may be broken so that the driving means and the airship holding means will be released and permit the craft to leave the catapult.

It is to be observed that the rear end of the third rail 5, terminates short of the rear ends of the rails 3, it being intended that the carriage 1 shall travel forward a predetermined amount upon said rails 3, before the shoes 8 and 11 come into engagement with the third rail. By this arrangement, the carriage and the aircraft carried thereby may move forward under the power of the latter until the shoes and third rail come into contact. When this takes place, however, the electric driving means D is automatically set in operation so that the ship may be caused to travel at a safe flying speed, before it is permitted to leave the carriage. When such a speed is attained, the aviator will signal to the operator of the launching apparatus and he will immediately operate the rheostat M to break the circuit of the propelling means and the electro-magnetic holding means E, the ship being then free to rise from the carriage. The arrangement em-

ployed for permitting the airship to move forward under its own power, before the driving means of the carriage comes into play, is highly advantageous, since by this arrangement the aviator will not start upon a flight, until his propeller is rotating at an operative speed.

It will be appreciated that the mechanism so far described may be employed to equal advantage for launching airplanes, whether the latter be of the usual type, or constructed to carry self-propelled torpedoes to be dropped into the water in an attack on an enemy craft, it being understood, that slight changes in the form of the several elements will necessarily be made according to the type of ship to be launched by the mechanism. In all cases, the electro-magnet E will preferably be surrounded by a housing 12 and said housing and magnet will be located in a longitudinal channel 13 formed in the top of the carriage 1; and when the apparatus is to be used for launching torpedo carrying aircraft, the top of the magnet E and the upper edge of the casing 12, will be provided respectively with seats 14 and 15 within which the torpedo T rests and serves as the sole connection between the airplane S and the catapult C, the torpedo being retained in place by the action of the electro-magnetic means provided. In most cases, the underside of the torpedo T will be provided with an auxiliary keel 16 which is receivable in keyways 17 formed in the top of the magnet and in the front wall of the casing 12. This construction prevents any undesirable movement of the torpedo relative to the car, yet at the same time permits it to rise and travel forward from the car at the proper time.

In operation, the carriage 1 is placed at the rear end of the tracks 3 with the airplane resting thereon, the shoes 8 and 11 being out of contact with the third rail 5. The switch M is now actuated to turn on the current and the propeller P of the airplane S is set in motion. When this propeller is traveling at a requisite speed, the carriage and ship are released so that the action of said propeller moves the two until the shoes 8 and 11 come into contact with the third rail 5. When this takes place, the driving means D of the carriage 1 is automatically set in motion and at the same time the electro-magnet means E comes into play to rigidly hold the ship upon the carriage. The airspeed indicator tells the aviator when he is traveling at a safe flying speed, and when such a speed is attained, he signals to the operator of the catapult to cut off the current. When the circuit is now broken by the means M, the magnetic attraction at E ceases so that the airship is free to rise from the carriage 1; at the same time the driving means D is thrown out of action, 130

but the carriage will glide, due to its momentum, and thus the ship may leave said carriage without any fluctuation in its speed. Obviously, the carriage 1 may be brought to a standstill in any preferred manner and although such an arrangement is not illustrated I prefer to equip the carriage in question with automatically operated brakes which come into action in ample time to bring it to a standstill before the end of the trackway is reached.

In the foregoing, I have stated that the third rail 5 terminates short of the rear end of the track rails 3, and that the current pickup shoes 8 and 11 do not touch said rail until the airplane and the carriage upon which it is mounted are initially set in motion by the propeller of the former. I wish it understood, however, that I do not wish to be restricted to this exact arrangement, since the three rails could well be of the same length, permitting the circuit of the mechanisms D and E to remain broken until it is required that the carriage be driven under its own power. The circuit could then be completed so that the same result would be obtained. Furthermore, I consider it fully within the scope of the present invention to provide independent circuits for the means D and E, so that the holding means E may become operative before the driving means D is set in motion, thus rigidly holding the airship upon the carriage while its propeller is initially starting the craft.

It will, of course, be understood that any preferred means may be employed for releasing the torpedo T from the ship 8, at the proper time, a pair of turn buttons 18 being shown in Figs. 4 and 5 for holding the torpedo in place upon the ship until it is required to drop the same. When this moment occurs, the two buttons 18 may be turned to a released position by pushing forward upon a foot pedal or the like 19 which is operatively connected with the turn buttons by wires or other suitable connections 20. Furthermore, although the improved launching mechanism may be constructed for launching all types of flying ships, the type preferably employed in connection therewith, will be of such construction as to permit it to remain floating on the surface of the water until the mother ship arrives to again take it on board, that is, if the device be used upon a battleship or the like, it being for this use that the invention is primarily intended, although it may be employed to equal advantage on land.

From the foregoing, taken in connection with the accompanying drawings, it will be obvious that my invention may be well employed under greatly varying conditions, and will be highly efficient. On account of

the several advantages flowing from the specific details of construction shown and described, such details are by preference employed, but I wish it understood that within the scope of the invention as claimed 70 numerous minor changes may well be made.

I claim:

1. A launching mechanism for aircraft comprising a car, and an electro-magnet on said car for holding the craft thereon until 75 the required speed has been attained, said craft having an armature attracted by said magnet.

2. A launching mechanism for aircraft comprising a car having electric operating 80 means, electro-magnetic means for holding the craft upon said car until the required speed has been attained, and means for then cutting off said operating means and said electro-magnetic means.

3. A launching mechanism for torpedo carrying aircraft comprising a car and an electro-magnet on said car for holding the torpedo by magnetic attraction and thus preventing flight of the aircraft until 85 the required speed has been attained.

4. A launching mechanism for torpedo carrying aircraft comprising a car, and an electro-magnet on said car for holding a torpedo of the craft, said electro-magnet 95 having a seat to receive the torpedo, thus preventing flight of the aircraft until the required speed is attained.

5. A launching mechanism for aircraft comprising a track, a carriage thereon, 100 means for connecting an aircraft to said carriage, means for propelling said carriage, and means for automatically throwing said propelling means into action when the aircraft propeller has started the ship and the 105 carriage forward.

6. A launching mechanism for aircraft comprising a track, a carriage movable from one end of said track to the other, electric means for propelling said carriage, and means for supplying current to said propelling means including a rail starting at a point spaced toward the end of the track from the starting point of the carriage, and a shoe on said carriage adapted to engage 110 said rail when the propeller of the aircraft starts the carriage forward.

7. An aircraft launching mechanism comprising a carriage, electric means for propelling said carriage, and electro-magnetic means on said carriage for holding the aircraft thereon by magnetic attraction, the circuits of both of said means being severable.

8. A launching mechanism for torpedo 125 carrying aircraft comprising a carriage, an electro-magnet carried by the upper side of said carriage for holding a torpedo of the craft, and a housing around said magnet having an open upper end, the upper edges 130

of the front and rear walls of said housing and the upper end of said magnet having alined depressions forming seats for said torpedo.

5 9. A structure as specified in claim 8, the upper side of said carriage having a pit in which said magnet and said housing are located, the front and rear walls of said pit having depressions in their upper edges to 10 clear the torpedo.

10 10. A launching mechanism for torpedo carrying aircraft comprising a carriage having a pit in its upper side, and an electro-magnet in said pit for holding a torpedo 15 of the craft, the upper edges of the front and rear walls of the pit and the upper end of said magnet having alined depressions, the

depression of said magnet forming a seat for said torpedo.

11. A launching mechanism for torpedo 20 carrying air craft comprising a car, and an electro-magnet carried by the upper part of said car for holding a torpedo of the craft, the upper end of said magnet having a channel shaped depression extending in the direction of movement of the car and forming a seat to receive said torpedo. 25

In testimony whereof, I have hereunto set my hand in the presence of two subscribing witnesses.

GODFREY LOWELL CABOT.
